UNITED STATES PATENT OFFICE.

STEPHEN H. SNYDER, OF WEST PITTSTON, PENNSYLVANIA.

MINE AIR STOP.

Application filed April 5, 1922. Serial No. 549,947.

To all whom it may concern:

Be it known that I, STEPHEN H. SNYDER, a citizen of the United States, residing at West Pittston, in the county of Luzerne and State of Pennsylvania, have invented certain new and useful Improvements in Mine Air Stops; and I do hereby declare the following to be a full, clear, and exact description of the invention, such as will enable others skilled in the art to which it appertains to make and use the same.

The present invention relates to means for controlling the ventilation of mines and has for its object the provision of an air stop, whereby a relief for excessive pressure is afforded without entailing partial or entire destruction of the stop when blasting.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a sectional detail, showing the invention applied,

Figure 2 is an elevation of the air stop,

Figure 3 is a horizontal section on the line 3—3 of Figure 2,

Figure 4 is an enlarged vertical section on the line 4—4 of Figure 2, the open position of the relief door being indicated by dotted lines, and

Figure 5 is a detail.

Corresponding and like parts are referred to in the following description and designated in the several views of the drawings by like reference characters.

The air stop comprises a frame 1 which conforms approximately to the outline of the drift or passage in which the stop is to be located. This frame is preferably constructed of wood, the several members being secured at the angles or corners in any substantial way.

A horizontal strip 2 is secured at its ends to the upright or side members of the frame 1 in any preferred way. Spaced vertical strips 3 are secured to the top member of the frame 1 and to the horizontal strip 2 and provide an opening which is normally closed by means of a door 4 which

is mounted to swing whereby to automatically open to relieve excessive pressure and to automatically close to retain the normal pressure necessary for proper ventilation. A suitable textile 5, such as canvas, covers the frame 1, with the exception of the relief opening which is closed by the door 4. Edge portions of the textile or canvas project beyond the frame 1, as indicated at 5^a, to insure a close joint between the frame 1 and the walls of the passage in which the air stop is located so as to prevent waste of air. Blocks 7 are attached to the frame 1 and serve to secure the frame in the located position and to brace the projecting marginal portions 5^a of the textile. The textile 5 is confined between the frame 1 and the blocks 7. When the device is in position, it is stayed by means of braces 6 which are interposed between the top member of the frame 1 and the floor of the mine.

The door 4 may be of any construction and usually consists of boards held together by means of cleats 9. The door 4 is pivotally connected at its upper end to the top of the frame 1 by suitable hinges 10. A cross piece 11 limits the closing of the door and maintains the same in predetermined position. A spring 12, preferably of the helical type, normally operates to hold the door 4 closed and is interposed between a bracket 13 and the door, said bracket being attached to the strip 2.

It will be understood from the foregoing, taken in connection with the accompanying drawings, that the invention results in the provision of an air stop for mines which is light and cheap in construction and which is automatic in action to relieve excessive pressure incident to blasting and to automatically close and prevent waste of normal air pressure essential for proper ventilation. When a blast is set off, the door 4 automatically opens against the tension of the spring 12 and when the excessive pressure due to the blast has been relieved, the spring 12 operates to automatically close the door and maintain the same in closed position against normal air pressure.

The spring 12 shown is of the expandible helical type and is reinforced and caused to work properly by a stay 12^a which consists of a rod passing therethrough.

What is claimed is:

1. A mine air stop having a frame, a textile covering for the frame, cleats securing

said textile covering to the frame, said textile covering having a portion projecting beyond the frame, said portion being disposed in contact with the outer edges of the 5 cleats to insure positioning of said portion by the cleats and a close joint between the frame and the wall of the mine, said stop having an opening therethrough, and a pressure-operable relief door normally closing 10 said opening.

2. A mine air stop consisting of a plurality of frame members joined together in reticulate form to constitute a frame, a covering for said frame, the frame between certain 15 of said members having an opening, a door carried by the frame and normally closing said opening, and means on the frame and coacting with the door to normally maintain the door closed and operable 20 by the door to permit opening of the latter upon predetermined air pressure.

3. A mine air stop consisting of a frame comprising a plurality of frame members

joined together in reticulate form, a covering for the frame, the frame having an opening through a portion thereof bounded by certain of said frame members, a door hinged to one of said frame members to normally close said opening, a crosspiece on the door extending beyond a side thereof to 25 coact with one of the frame members to limit closing movement of the door, a bracket extending forwardly from one of the frame members, a rod connected to the door and slideable through said bracket, and an expansive spring on said rod and engaging 30 said bracket at one end and said door at the other end to permit opening of the door upon predetermined pressure within the mine.

In testimony whereof I affix my signature in presence of two witnesses.

STEPHEN H. SNYDER.
